No. 656,079.

Patented Aug. 14, 1900.

E. P. ARSNEAN.

DERRICK.

(Application filed Mar. 24, 1900.)

(No Model.)

UNITED STATES PATENT OFFICE.

EDWARD P. ARSNEAN, OF DULUTH, MINNESOTA.

DERRICK.

SPECIFICATION forming part of Letters Patent No. 656,079, dated August 14, 1900.

Application filed March 24, 1900. Serial No. 10,104. (No model.)

To all whom it may concern:

Be it known that I, EDWARD P. ARSNEAN, a citizen of the United States, residing at Duluth, in the county of St. Louis and State of Minnesota, have invented certain new and useful Improvements in Derricks; and I do hereby declare the following to be a full, clear, and exact description of the invention, such as will enable others skilled in the art to which it appertains to make and use the same.

My invention relates to improvements in derricks; and it comprises a base, a derrick proper mounted thereon, a cross brace or bar on the said derrick, an anchor-beam pivotally secured to the said base, and means for adjustably securing the cross-brace to the anchor-beam at different points along its length, whereby the derrick may be varied in its position with respect to the base and may be positively held against movement in either direction by the said brace.

It also consists in certain other novel constructions, combinations, and arrangements of parts, as will be hereinafter fully described and specifically claimed.

In the accompanying drawings, Figure 1 represents a side elevation of a derrick constructed in accordance with my invention. Fig. 2 represents a front elevation of the same. Fig. 3 represents a detail sectional view through one of the sills of the derrick-base, showing the manner of mounting one end of the anchor-beam. Fig. 4 represents a detail view showing the socket for receiving the lower end of one of the derrick beams or poles, and Fig. 5 represents a detail view of one of the blocks used upon the derrick.

My improved derrick is of exceedingly-simple construction, it being designed to supply derricks which can be easily and readily handled, which can be adjusted to the various positions in which it may be used, and which, although light in construction, will be sufficiently strong for the purposes required.

The derrick comprises a derrick-frame proper, as 1, formed of poles or beams 2 2, and which may be secured at their top by means of a cross-head piece, as 3, or, if desired, may be beveled and secured to each other. The lower ends of the derrick-poles 2 2 are preferably reduced and formed with tenons, as 4, upon their ends, which are adapted to enter

and rest in sockets or mortises 5, formed in the sill of the derrick-support. The derrick-poles 2 rest loosely in the sockets 5, but are prevented from being accidentally displaced by means of short slack chains, as 6 6, which are secured in eyes in the sill and derrick-poles. This allows of sufficient play for the adjustment of the derrick-frame to different heights and yet forms a simple joint between the parts. The base or support of the derrick is preferably constructed of two sills, as 7 7, although any number may be used as desired. Two sills are sufficient for ordinary purposes, and these may be connected by a series of cross beams or pieces 8 8. I preferably employ four of these pieces 8 to give sufficient strength and rigidity to the derrick-base. Near the upper end of the derrick 1 and between the poles 2 2 I preferably mount a pulley or sheave 9. About midway of the height of the poles 2 a cross-beam, as 10, is secured to both of the derrick-poles 2 2.

The derrick is adapted to be adjusted and braced in different positions by means of an anchor-beam, as 11, which is pivoted, as at 12, at its lower end to one of the sills 7, its other end being provided with a series of apertures, as 13, which may be made to register with an aperture 14 in the cross-beam 10, a pin 15 being inserted through the registering apertures to secure the anchor-beam to the derrick. By adjusting the pin to different holes in the anchor-beam the derrick may be held at different heights. The derrick may be further guarded against strain and braced in position by means of a guy-rope or chain 16, secured at one end to the top of the derrick and running at its other end to any suitable anchorage. The lower end of the anchor-beam 11 is preferably pivoted in a strap-staple, as 17, provided with a bolt 18, which extends through the sill 7 and is secured therein by means of a nut. A pivot-pin, as 19, passes through the staple 17 and the lower end of the anchor-beam. The draft cable or chain 20 employed preferably passes from the top of the derrick, to which it is secured, downwardly and about a hoisting-block 21, thence upwardly and over a sheave 9, from which it passes downwardly again and around a swiveled block 22, secured to the sill 7. The cable is thence carried off where suit-

able power may be applied to it for lifting the logs to be hoisted. The swivel-block 22 is provided with a hook 23, which is swiveled to the said block, the said hook being adapted 5 to engage an eyebolt secured to the sill 7. The block 22 is also supplied with a swiveled eye 25 at its upper end, which is connected, by means of the cable or rope 26, with an eyebolt 27, secured to the cross-beam 10. This 10 cable or rope 26 operates to hold the swivel-block 22 in a vertical position at all times, and especially when there is any strain upon the draft-cable. The hoisting-block 21 may be provided with a crotch-chain, as 28, having hooks 29 29 at its ends, of any desired 15 construction. A desirable way of forming these hooks is to supply them with eyes, as 30, to which may be secured ropes 31 for guiding the said hooks.

20 A derrick of this character is especially well adapted for lifting logs, and when so used the strain of holding the derrick up is chiefly on the guy line or cable 16. The adjustable anchor-beam is of great importance, for it is 25 adapted not only to hold the derrick in position when the guy-line is loose, but when moving the machine from point to point, since without it there would be nothing to prevent the derrick from falling backward or forward. When the derrick is held in its vertical position and is being moved, it is likely 30 to be knocked over by striking trees as it passes from place to place; but the anchor-beam will prevent such difficulty from arising.

35 Having thus described my invention, what I claim as new, and desire to secure by Letters Patent, is—

1. A derrick, comprising a base, a derrick proper movably [mounted thereon, a cross 40 brace or bar on the said derrick, an anchor-beam pivotally secured to the said base, means for adjustably securing the cross-brace to the anchor-beam at different points along 45 its length, whereby the derrick may be varied in its position with respect to the base, the construction being such that the derrick will be positively held against movement in either direction by the said brace.

2. A derrick comprising a base, a derrick 50 proper formed of poles joined together at their tops and provided with tenons at their lower ends adapted to rest in sockets formed in the base, slack chains for connecting the

derrick-poles with the base so that they cannot be accidentally displaced from their sockets, and means for bracing the derrick in position, substantially as described. 55

3. A derrick comprising a base having mortises or sockets formed therein, a derrick proper mounted upon said base and having tenons engaging said sockets, the said tenons being rounded at their ends so that they may have a pivotal movement in said sockets, a guy- rope for holding the upper end of the derrick against lifting strains, and an anchor-beam pivoted to the base and adjustably secured to the derrick for further bracing the same, substantially as described. 60

4. A derrick comprising a base, a derrick proper formed of beams joined together at 70 their tops and resting in sockets at their lower ends, a cross brace or beam upon the said derrick proper, an anchor-beam pivoted at one end to the base and provided at its other end with a series of apertures, a pin 75 for adjustably connecting the apertured end of the anchor-beam with the cross-beams of the derrick, whereby the derrick will be prevented from tipping forward or backward, a sheave or pulley mounted at the apex of the 80 derrick, a swivel-block secured to the base, and a hoisting-block for receiving a hoisting-cable, substantially as described.

5. A derrick comprising a base, a derrick proper formed of derrick-poles secured together at their upper ends and spread apart at their lower ends, a brace-rod connecting the said poles about midway of their length, an anchor-beam for bracing the said derrick and adjustably connected with the cross-beam, a sheave mounted at the apex of the derrick, a swivel-block secured to the base, a cable or rope connecting the swivel-block with the cross-brace so that the said block will be held vertical when the draft-cable is 95 slack, a hoisting-block, a crotch-chain, hooks carried thereby, and a draft cable or rope passing over the blocks and sheaves for raising and lowering the hoisting-block, substantially as described. 100

In testimony whereof I hereunto affix my signature in presence of two witnesses.

EDWARD P. ARSNEAN.
